UNITED STATES PATENT OFFICE.

ALBERT L. MARSH, OF LAKE BLUFF, ILLINOIS, ASSIGNOR TO HOSKINS COMPANY, OF CHICAGO, ILLINOIS, A CORPORATION OF ILLINOIS.

ELECTRIC FURNACE.

No. 882,788.

Specification of Letters Patent.

Patented March 24, 1908.

Application filed September 19, 1907. Serial No. 393,730.

To all whom it may concern:

Be it known that I, ALBERT L. MARSH, a citizen of the United States, residing at Lake Bluff, in the county of Lake and State 5 of Illinois, have invented a new and useful Improvement in Electric Furnaces, of which the following is a specification.

The object of my invention is to provide a novel construction of electric furnace where- 10 by the intensity of heating the resister shall be rendered regulable by forming it of surface-contacting sections and equipping it with means for compressing the sections together and varying the degree of com- 15 pression at will to vary accordingly the re- sistance.

In the accompanying drawings, Figure 1 shows my improved furnace, in one form of embodiment of the invention, by a ver- 20 tical section, partly in elevation, and Fig. 2 is a plan view of the same.

The particular construction of the furnace illustrated in the drawing represents one of various forms of embodiment of my invention 25 of which it is susceptible, all of which are intended to be included as within the same. The essence of my invention, however, lies in adapting the principle of variable electric 30 resistance, under variation in contact-pressure of the sections of a sectional resister, to produce a contact-resistance type of electric furnace.

In the drawings, which present my improved furnace in cylindrical shape, 3 is 35 the casing of insulating material, as magnesite, fire-brick, or the like, having a closed base and an open top provided with a disk-shaped cover 4, which may be composed of asbestos-board, the cover being 40 securely but removably fastened in place by bolts 5 passing through the wall of the casing to project beyond its upper end through openings in the cover near its edge to receive nuts 6 to be screwed down against the cover. 45 The wall and base of the casing are reinforced by a sheet-metal sheathing 7, and the casing is shown to be supported on legs 8 between which depend from the bottom of the sheathing rigid arms 9 converging to aline 50 with a central opening 10 provided in the casing-base, these arms containing at their junction a stationary nut 11 in which works a screw 12 against a bearing 13. In the casing is contained the resister 14, forming 55 the furnace-lining, made up of separate

contacting solid pieces or sections 15 of suitable material, preferably carbon, though they may be of surface-oxidized metal, or compounds of metals, such as the oxids and sulfids of metals which are conductors of 60 electricity at ordinary temperatures, the end-sections 16 and 17 being, preferably composed of graphite and having terminal- 65 posts 18 and 19, of the same material, projecting from them, respectively. As shown, 70 the sections 15 and 16 are in the form of flat annular plates or rings, the upper section 16 being thicker than the sections 15, but like the section 17 in thickness though not annular, being a disk-shaped block; and 75 it seats on the inner surface of the casing-base, through the central opening in which its terminal-post 19 passes to engage at its lower end with the bearing 13. The bodies forming the resister-sections conform to and 80 fit within the casing 3, composing a pile or stack therein confined between the casing-base and cover 4, through an eccentric opening 20 in which the terminal-post 18 of the upper section 16 protrudes. The rings 16, 17 85 form a wall or heating chamber 21, with which a central opening 22 in the cover coincides through which to introduce a crucible (not shown) the contents of which are to be subjected to the furnace heat. The 90 section 17 affords a closing head to the furnace-chamber.

The leads for conducting electrical current-supply of suitable voltage and power to and from the furnace are shown at 23 and 24, 95 each terminating in a metal (copper) sleeve 25, one to fit closely about the upper post 18 and the other to fit similarly about the post 19.

By turning the screw 12 in one direction or 95 the other the register-sections, which are compressed between it and the cover 4, will be loosened or tightened as to their surface-contact with each other, to increase or de- 100 crease the resistance for regulating the in- tensity of heating the furnace, which the construction enables to be performed to a nicety.

The electrical resistance of the resister- 105 sections varies inversely as the pressure, so that the screw 12, or any other suitable me- dium for regulating the degree of compres- sion, affords a ready medium of controlling the heat of the furnace.

As advantages of the contact-resistance 110

furnace thus described over the known solid-carbon resister type, the following may be mentioned: Greater resistance per unit of length for a given cross-section of resister; 5 lesser sensitiveness of the furnace to reduction in cross-section of resister due to burning, since the resistance depends more on the number of sections in series and the pressure than on the area of contact; the furnace-resister is more durable under heat, since a larger cross-section may be used for a given 10 resistance in the furnace and the time of consumption of the resister is lengthened; the furnace is of non-fragile construction, differing 15 in that respect from a solid-carbon resister, which is liable to fracture and thus break the circuit, whereas in my contact-section construction the cracking of one or more of the plates or blocks makes little, if 20 any, difference in the operation of the furnace; and, finally, the resister is more readily renewed when burned out, the sections merely being required to be dropped into place and the regulating screw turned up, 25 while the solid-carbon resister, which is a mere rod, must be carefully adjusted in place and connected in a manner to avoid the exertion of torsional or breaking strains upon it.

30 My improved type of furnace has a great advantage over the known granular-carbon resister in starting it or bringing up the heat, and in the matter of regulation after attaining the proper high temperature. The resistance in the granular-carbon type of furnace is very high when the furnace is cold and much lower when it is at white heat; therefore, with a single voltage which is right 35 for the furnace at full heat, the furnace is slow of heating, since the power put in is small until the high temperature is attained. On the other hand, with my contacting-section type of resister, the resistance may be decreased or increased at will and the speed 40 in heating as well as the final temperature attained are under the control of the operator.

45 What I claim as new, and desire to secure by Letters Patent, is:

1. An electric furnace, the lining of which 50 forms a variable-resistance rheostat constituting the furnace-resister, said lining consisting of contacting bodies of solid electro-conductive material in series, with compressing means for the sections adapted to 55 increase and decrease the pressure-contact

between said bodies, for the purpose set forth.

2. An electric furnace, the lining of which forms a variable-resistance rheostat constituting the furnace-resister, said lining 60 consisting of contacting bodies of solid electro-conductive material in series, and a compression-device working against said series of bodies endwise thereof to increase and decrease the pressure-contact between them, 65 for the purpose set forth.

3. An electric furnace, the lining of which forms a variable-resistance rheostat constituting the furnace-resister, said lining 70 consisting of flatwise contacting rings of electro-conductive material and a head of similar material, with compressing means for the lining adapted to increase and decrease the pressure-contact between the sections thereof, for the purpose set forth.

4. An electric furnace having a casing of insulating material provided with a sheathing of metal and the lining of which forms a variable-resistance rheostat constituting the furnace-resister, said lining consisting of a 80 series of flatwise-contacting rings of electro-conductive material and a head of similar material, a cover on said casing, and a compression-screw working against said head, for the purpose set forth.

5. In an electric furnace, the combination of a resister composed of a series of contacting rings of solid carbonaceous material forming the furnace-chamber provided with a head of similar material having a terminal-post extending from it, the outer ring of said series having a similar post, said posts affording lead-connections with the resister, a metal-sheathed casing of insulating material inclosing said resister, and through the base 95 of which the terminal-post on said head protrudes, a cover removably secured on said casing and through which the other terminal-post protrudes, legs supporting the furnace, arms depending from the casing, a 100 nut supported by said arms, a screw working in said nut, and a bearing supported to be engaged by said screw and forming a seat for the terminal-post on said head, for the purpose set forth.

ALBERT L. MARSH.

In presence of—

W. T. JONES,
R. A. SCHAEFER.
